DESIGN FOR A LOUVERED FLUORESCENT LIGHTING FIXTURE

Carl X. Meyer, St. Louis, Mo., assignor to Day-Brite Lighting, Inc., St. Louis, Mo., a corporation of Missouri

Application April 26, 1948, Serial No. 145,960

Term of patent 14 years

(Cl. D48—23)

To all whom it may concern:

Be it known that I, Carl X. Meyer, a citizen of the United States and a resident of the city of St. Louis and State of Missouri, have invented a new, original, and ornamental Design for Louvered Fluorescent Lighting Fixture, of which the following is a specification, reference being had to the accompanying drawing, forming part thereof.

Fig. 1 is a top plan view of a louvered fluorescent lighting fixture, showing my new design,

Fig. 2 is a bottom perspective view thereof; and

Fig. 3 is an enlarged end elevational view looking at the opposite end from that shown in Fig. 2.

I claim:

The ornamental design for a louvered fluorescent lighting fixture, substantially as shown.

CARL X. MEYER.
